OUTBOARD DRIVE FOR MOTOR BOATS

Charles Samuel Johnson, Parnell, Auckland,
New Zealand

Application May 8, 1940, Serial No. 334,030

11 Claims. (Cl. 115—17)

This invention relates to outboard drives for motor boats of the smaller types used for pleasure, sport and general purposes, the objects of the invention being the provision of an improved form of outboard drive wherein the steering wheel of the boat which may be located at a distance from the outboard drive, will give steering control and retractive control thereof.

With outboard motors, the propeller is located at the bottom of a suspension column of tubular form through which a drive shaft makes a connection between the propeller and the engine mounted at the top of the column, it being important that the outboard motor be capable of swinging rearward from the transom of the boat if the bottom of the column should encounter a floating object or the sea bottom or beach, as otherwise the motor will be liable to serious damage.

Outboard motors are very subject to striking the shore when run into shallow water due to the propeller usually being well below the bottom of the boat.

The present invention has been devised for the purpose of providing an improved outboard drive wherein the movements of the steering wheel give simultaneous rudder and retractive control, so that in the event of the boat operator seeing some object which the boat will have to pass over, or when the depth of water shallows to an extent which would not be safe, he can completely retract the propeller and suspension column from the water by mere operation of the steering wheel, the retractable characteristics also enabling the engine to be more easily started up with the propeller out of the water, to be run idle as for tuning-up purposes, and enable a clutch like action to be achieved when the propeller and the suspension column are lowered into the water with the engine running.

Broadly the invention comprises an outboard drive for motor boats wherein operation of the steering wheel or steering control means of the boat, is adapted to simultaneously effect rotary rudder movement and radial retractive movement from the water of the suspension column on the outer end of which the rudder and the propeller are disposed.

In describing the invention reference will be made to the accompanying drawings in which

Figure 1 shows a partial elevation of the outboard propeller drive mechanism with a portion of the thrust ring broken away to show the ring gear and stay rail behind same,

Figure 2 is a partially sectioned plan view of Fig. 1.

Figure 3 is a sectional side elevation of Fig. 1 including the propeller and its drive case,

Figure 4 is a sectional view on line A—B of Fig. 1.

Figure 5 is a sectional plan view on line C—D of Fig. 4,

Figure 6 is an enlarged sectional view of the retraction stop mechanism,

Figure 7 shows the outboard propeller drive mechanism as applied to the transom of a boat, the simultaneous retractive movement and rudder movement being indicated and

Figure 8 is a similar view to Fig. 7 but showing the fully retracted position whereat the apparatus can be locked by the retractive stop mechanism.

The invention comprises a suspension base 1 of circular drum form from one side of which a boss 2 will extend, the periphery of the opposite side of the base 1 having an annular stay rail 3 extending therefrom which also includes at its periphery a gear ring 4, the stay rail 3 and the gear ring 4 being concentric with the boss 2.

The interior side 5 (see Fig. 3) of the base 1 has a bearing face 6 for a suspension case 7 which is adapted to be rotatable within said base 1 and is held in place by a bearing ring, 8, studs and nuts 9 which secure the latter to the base 1 also being usable as the means for securing the base 1 to the transom 10 of the boat, the boss 2 being adapted to project within the boat by way of the hole 11 cut through the transom 10.

The boss 2 may be used to carry a tube (not shown) to locate or centre the engine within the boat, small powered engines being, if desired, directly attached to the boss 2.

The suspension case 7 is of basin shape with conical rim 12 engaged by the bearing ring 8, the inside of the rim having an internal gear ring 13, the end of the suspension case 7 opposite to its rim 12 carrying a bearing 14 and a mounting base 15, the latter and the bearing 14 being concentric with the suspension base 1.

The bearing 14 revolvably supports the horizontal drive shaft 16 which passes through the suspension case 7 and through the boss 2 of the suspension base 1, to be coupled directly or otherwise connected in any known manner to the engine which is mounted within the boat, the boss 2 being capable of acting as further bearing means for the shaft 16 if so desired, although for the most part in general cases, this will not be necessary.

Secured by setscrews or like 17 to the mounting base 15 of the suspension case 7 there will be the gear cover 18 and extending at right angles therefrom there will be the suspension column 19, the gear cover 18 enclosing the bevel pinion 20 on the end of the horizontal drive shaft 16, which is in mesh with a bevel pinion 21 on the top of a vertical intermediate shaft 22, such shaft 22 being supported by a thrust bearing 23 in the upper end of the cylindrical bore 24 of the suspension column 19.

The suspension column 19 will extend to just beyond the annular stay rail 3 and will terminate in a worm gear housing 25, the suspension column also having as integral portions thereof, a worm housing 26 and a thrust block 27.

The worm housing 26 is disposed to one side of the worm gear housing 25 (see Fig. 4) and revolvably holds a worm 28 and its drive shaft 29 parallel to the horizontal drive shaft 16.

The worm drive shaft 29 projects through the inner end of the worm housing 26 and has a pinion 30 secured thereto which meshes with the gear ring 4 of the suspension base 1, the worm housing 26 having a cover 31 at its outer end, the worm 28 being in mesh with the worm gear 32 which is revolvably disposed within the worm gear housing 25, said worm gear 32 being secured at the top end of the tubular rudder stock 33.

A thrust ring 34 bears at its inner face against the annular stay rail 3, said ring 34 having a flange 35 at its inner edge to retain it concentric with the suspension base 1, its outer face having two lugs 36 (see Fig. 5) extending therefrom at the point where the suspension column 19 crosses same, these lugs 36 forming the means whereby bolts 37 secure the said suspension column 19 via its thrust block 27 to the thrust ring 34.

The suspension column 19 has column tube 38 rigidly secured to within its bore 24, securement being obtained by such means as a bolt 39 (see Fig. 5) extending across the thrust block 27 and clamping bushes 40 and 41 through which it passes so as to clamp the said bushes 40 and 41 against the outer wall of the tube 38.

The suspension tube 38 extends through the worm gear housing 25 and the tubular rudder stock 33 and at its bottom end is rigidly secured to the propeller drive casing 42, this latter being of known form enclosing the known bevel gears and propeller shaft by which the drive from the vertical intermediate shaft 22 is transmitted to the propeller 43.

The tubular rudder stock 33 passes downward from the worm gear 32 through a worm housing cover 44, the stock 33 having an anti-cavitation plate 45 as an integral portion thereof below which there is the rudder 46 so shaped as to extend around the propeller drive casing 42 and to back and front of the stock 33 (see Fig. 3).

The retraction and rudder control shaft 47 (see Fig. 2) is supported by a bearing which will be integral with the suspension base 1, this shaft 47 extending to within the suspension case 7 whereat it has a pinion 48 which meshes with the internal gear ring 13 of said case 7, the other end of the control shaft 47 being located within the boat.

Any suitable known connection can be made within the boat between this control shaft 47 and the steering wheel which may be located at a forward position within said boat, so that the control shaft is rotated by rotation of the steering wheel, a sprocket wheel 50 on the end of the

shaft 47 being shown by way of illustrating one form of known connection, a sprocket chain (not shown) passing between this sprocket 50 and the steering wheel over sheaves and such like.

Retraction stop mechanism is provided so that when the propeller 43 has been retracted from the water to the desired extent, such mechanism will operate to hold the propeller in the retracted position such as shown in Figure 8.

The retraction stop mechanism comprises (see Fig. 6) a bore 51 extending into the annular stay rail 3 at one of its ends and through a boss extension 52 of the suspension base 1 at its other end so that the said boss can project through the transom 10.

Within this bore 51 there is a slidable plunger 53 to which a cable, Bowden wire or like 54 is attached, a compression spring 55 being disposed between the plunger 53 and a cap or nut 56 which screws into the bore 51 at the boss end thereof, the action of the spring 55 being to force the plunger 53 into contact with the thrust ring 34, there being a hole 57 within the ring 34 and the thrust block 27 into which the plunger 53 will be projected when the said hole 57 coincides with the position of the plunger 53 which will be located on the horizontal centre line of the suspension base 1.

The cable, Bowden wire or like 54 will pass to a position adjacent to the steering wheel so that the boat operator can effect withdrawal of the plunger 53 when desired.

There could obviously be two or more of these retraction stop mechanisms adapted for simultaneous operation so that the propeller 43 could be retracted and held to the port side of the boat or to the starboard side as shown in Fig. 8 and in cases it may be desired to be able to retract and hold the propeller so that it extends upward from the suspension base 1.

On the other hand, although the retractive stop mechanism is a convenience, it is not essential and could be eliminated.

With outboard motors, the propeller 43 and its drive casing 42 swivel around along with the rudder 46, but with the apparatus of the invention, the propeller 43 and the drive case 42 thereof will remain stationary and fixed to the suspension column 19 and thereby give more rigid support to the propeller end of the suspension column.

As an alternative, the propeller 43 and its drive casing 42 may swivel along with the rudder 46, this action being obtained by removing the bolt 39 and the clamping bushes 40 and 41 and allowing the suspension column 19 to act as a bearing for the suspension column tube 38, the tubular rudder stock 33 and the suspension column tube 38 being clamped together in known manner as by a setscrew or like, or could be made as one integral unit.

The term "suspension column" is broadly used in the art to refer to the whole combination of units of apparatus comprising the suspension column 19, rudder stock 33, suspension tube 38, rudder 46, drive case 42, propeller 43 and other parts attached to these units, but for clarity purposes, a distinction will be formed by referring to the rudder 46, suspension tube 38, propeller drive casing 42 and propeller 43 as being the "outer portion" of the suspension column.

In use or operation, the apparatus will be attached by its suspension base 1 to the outside of the transom 10 of the boat and the horizontal drive shaft 16 is coupled to the engine located

at suitable position within the boat, such position being dependent on varying conditions such as weight and power of the engine and the size and type of the boat, the inboard engine having various known advantages over the substantially exposed engines as incorporated in outboard motors.

The controls for the engine and for the outboard drive may be located at the fore part of the boat as is usual particularly in the case of speed boats, the steering wheel being connected to the control shaft 47 in such manner that the rotation of the steering wheel will effect simultaneous rotation of said control shaft 47 and its pinion 49.

The cable, Bowden wire or like 54 will pass to the control station whereat a simple known type of lever will be disposed to effect withdrawal of the plunger 53 of the retraction stop mechanism and also release of said plunger 53.

When the steering wheel is rotated, the control shaft 47 also rotates so that its pinion 49 in mesh with the internal gear ring 13 causes the suspension case 7 to also rotate within the suspension base 1.

Such rotation of the suspension case 7 will cause the suspension column 19 and the propeller 43 to swing radially to right or left from the normal vertical and downward position in accordance with the direction of rotation of the steering wheel, but when the suspension case is rotated, such movement will cause the pinion 30 of the worm drive shaft 29 to be rotated due to being in mesh with the gear ring 4 of the stationary suspension base 1, such rotation of the worm shaft 29 causing the worm 28 to rotate the worm gear 32 and as the latter is attached to the top of the rudder stock 33, the latter and the rudder 46 are rotated around the suspension column tube 38, the steering of the boat being thus effected with at the same time partial retraction as shown in Fig. 7.

The ratio of the various gears effecting rotation of the rudder 46 will preferably be such that a ninety degree radial movement as shown in Fig. 8 of the drawings will have also effected a ninety degree rotation of the rudder 46.

The radial retraction of the suspension column 19 to the position as shown in Fig. 8 will cause the hole 57 to coincide with the plunger 53 and this latter will be pushed into said hole 57 by the compression spring 55 and thus said plunger 53 will hold the suspension column in the retracted position until the operator withdraws same from engagement within the hole 57.

The main thrust caused by the drive of the propeller 43 will be transmitted from the suspension column and its thrust block 27 to the thrust ring 34, which in turn will transmit the thrust through the annular stay rail 3 and the suspension base 1 to the transom 10.

The complete retraction of the suspension column from the water will have obvious advantages and the holding of the apparatus in retracted position is advantageous in the case of boats which are to be transported overland on trailers and the like, the suspension column being moved to the position as shown in Fig. 8, or if so desired could be moved to a position vertically above the suspension base 1.

With the suspension column tube 38 free to rotate within the suspension column 19 and clamped to the rudder stock 33, the action will be the same as described except in that the

drive case 42 and the propeller 43 will swivel along with the rudder 46.

I claim:

- 5 1. An outboard drive for motor boats comprising a suspension base to be fastened to a boat, a suspension column rotatively mounted on said base, a rudder rotatively mounted on said column and means for rotating at substantially the same time said column on said base and said rudder on said column.
- 10 2. An outboard drive for motor boats comprising a suspension base to be fastened to a boat, a suspension column rotatively mounted on said base, a rudder rotatively mounted on said column and means for rotating at substantially the same time and to substantially the same degree said column on said base and said rudder on said column.
- 15 3. An outboard drive for motor boats comprising a suspension base to be fastened to a boat, a suspension column rotatively mounted on said base, a rudder rotatively mounted on said column and means for rotating at substantially the same time said column on said base and said rudder on said column and manually operated means controlling said means for rotating said column and rudder.
- 20 4. An outboard drive for motor boats comprising a suspension base for securement to the transom of the boat, a suspension case adapted to be rotatable within the suspension base and having a suspension column extending at right angles therefrom, a rudder, column tube, propeller drive casing and propeller at the outer end of said suspension column, propeller drive means passing from the engine within the boat to the propeller on the outer end of the suspension column, means which when rotated effect radial movement of the suspension column around the suspension base and means which, when the suspension column is radially moved around the suspension base simultaneously effect rotary movement of the rudder, column tube, propeller drive case and the propeller on said suspension column.
- 25 5. An outboard drive for motor boats comprising a suspension base to be fastened to a boat, a suspension column mounted on said base to rotate relative thereto about a horizontal axis, a rudder rotatively mounted on said column, a propeller mounted on said column, drive means for said propeller extending through said base and column and means for rotating substantially simultaneously said column and said rudder.
- 30 6. An outboard drive for motor boats comprising a suspension base to be fastened to a boat, a suspension casing rotatively mounted upon said base, a suspension column secured to said casing at one end thereof and extending at right angles thereto, a rudder rotatively mounted upon said column at the free end thereof, a propeller located at the free end of said column, drive means for said propeller extending through said base casing and column, means for rotating said casing relative to said base and thereby swinging said column about a horizontal axis and means cooperating with said rudder effective upon such swinging of said column to rotate said rudder.
- 35 7. An outboard drive for motor boats comprising a suspension base to be fastened to a boat, a suspension column rotatively mounted on said base having a circular gear track, a rudder rotatably mounted on said column, a manually operated control shaft rotatably mounted in said base, a pinion fixed to said control shaft mesh-
- 40
- 45
- 50
- 55
- 60
- 65
- 70

ing with said gear track to rotate said column relative to said base and means for rotating said rudder substantially simultaneously with the rotation of said column about said base.

8. An outboard drive for motor boats comprising a suspension base to be fastened to a boat, a suspension column rotatively mounted on said base having a circular internal gear track, a rudder rotatably mounted on said column, a manually operated control shaft rotatably mounted in said base, a pinion fixed to said control shaft meshing with said gear track to rotate said column relative to said base and means for rotating said rudder substantially simultaneously with the rotation of said column about said base.

9. An outboard drive for motor boats comprising a suspension base to be fastened to a boat, a suspension column rotatively mounted on said base having a circular gear track, a rudder rotatably mounted on said column, a manually operated control shaft rotatably mounted in said base, a pinion fixed to said control shaft meshing with said gear track to rotate said column relative to said base, a gear mounted on said rudder, a second gear meshing with said first meshing gear, a shaft upon which said second gear is fixed, a pinion carried by said shaft and said suspension base having a gear track with which said last named pinion meshes so that upon rotation of said column about said base said rudder is simultaneously rotated.

10. An outboard drive for motor boats comprising a suspension base to be fastened to a boat, a suspension column rotatively mounted on said base having a circular gear track, a rudder rotatably mounted on said column, a manually operated control shaft rotatably mounted in said base, a pinion fixed to said control shaft mesh-

ing with said gear track to rotate said column relative to said base, a propeller mounted upon said column, means for driving said propeller extending through said base and said column, a gear connected to said rudder and means cooperating with said base and said last mentioned gear for rotating said propeller and rudder on said column when said column is rotated relative to said base.

11. An outboard drive for motor boats comprising a suspension base to be fastened to a boat, a suspension casing rotatably mounted upon said base having a circular gear track, a suspension column secured to said casing at one end thereof and extending at right angles thereto, said base having also a circular gear track, a worm gear located upon said column, a second worm gear meshing with said first named worm gear, a shaft to which said last-named worm gear is fixed, a pinion upon said shaft meshing with said gear track upon said base, a tubular rudder stop secured to said first named worm gear, a rudder carried by said stop, a suspension tube mounted in said suspension column, a propeller and a drive casing therefor secured to said suspension tube, a thrust block upon said suspension column, a thrust ring secured to said block, said base having an annular stave rail cooperating with said thrust ring and against which said thrust ring bears, drive means for said propeller extending through said base, casing and column, a pinion meshing with said gear track in said casing, a shaft upon which said last named pinion is mounted and manually operated means for rotating said shaft and thereby said casing and column relative to said base.

CHARLES SAMUEL JOHNSON.
